ATTORNEY

UNITED STATES PATENT OFFICE.

WILLIAM E. RAWLINGS, OF NEAR SAN JOSE, CALIFORNIA.

JACK.

Application filed January 26, 1927. Serial No. 163,753.

This invention relates particularly to a device for raising a disc plow or similar implement from the ground whereby to permit rotation of its axle and sharpening of the discs.

It is one object of the invention to provide a device for the character indicated that may be quickly and easily applied to the implement between any two discs and allow the free rotation of the axle and discs thereon.

It is another object of the invention to provide a device of the character indicated that will be economical to manufacture, strong, durable, and highly efficient in its practical application.

In the drawing:—

Figure 1 is a side elevation of the device in operative relation to a disc and axle.

Figure 2 is a perspective illustration of a portion of the device, greatly enlarged.

Referring more particularly to the drawing, I show at 1 a lever pivotally connected at one end as 2 to a plate 3. The other end is provided with a handle 4, and spaced back from the handle 4 is a leg 5 pivotally connected to the lever as at 6 and to a foot plate 7 as at 8, the two pivots 6 and 8 consisting of hinges arranged to operate in opposite directions to each other.

On the upper side of the lever 1 is mounted a block 9 arranged to lie in a horizontal plane when the leg 5 is in a vertical position and having an annular socket formed in its upper surface as at 10.

The reference 11 indicates a portion of the axle of a disc, and upon which are mounted the discs as 12 separated by spacer sleeves as 13 in the usual manner. These sleeves are usually more or less rough on their outer surfaces and not adapted to rotate smoothly in a bearing, therefore I provide a circular bearing member as 14 provided with hubs as 15, the whole being formed in two parts as shown and bored to tightly engage the sleeve 13. When in position this member is secured in place in any suitable manner as by clamps 16.

When the discs have become dulled by use one of these jacks is placed between two discs near each end of the implement, the bearing members 14, 15, 16 having previously been clamped in position on the sleeve 13, and a quantity of lubricating grease having been placed in the socket 10. Upon raising the lever 1 the said socket engages the part 14 and the leg 5 assumes a vertical position thereby supporting the axle 11 in a raised position and lifting the discs free from the ground. This having been accomplished the axle and all of the discs thereon may be rotated freely in any suitable manner, permitting the discs to be ground to a sharp edge without removing the same from the axle.

It is to be understood, of course, that while I have herein shown and described but one specific form of my invention, changes in form, construction and method of assembly and operation may be made within the scope of the appended claims.

I claim:

1. A jack for a revoluble axle comprising a lever having a leg mounted thereon adjacent one end and having a bearing formed therein between the leg and the other end, and a bearing member mountable upon the axle to rotate therewith and journaled in said bearing.

2. A jack for a revoluble axle comprising a lever having a plate pivotally mounted on one end thereof at right angles to the plane of movement of the lever, a leg pivotally mounted thereon adjacent the other end and movable in the plane of movement of the lever, the said lever having a bearing formed therein between the leg and plate, a bearing member mountable upon an axle to rotate therewith and journaled in said bearing, and a plate pivotally mounted upon the free end of the leg in a plane parallel with the plane of said first mentioned plate.

WILLIAM E. RAWLINGS.
